BY

Phelan, Donnelly

ATTORNEY.

UNITED STATES PATENT OFFICE

JOHN AJEMIAN, OF DETROIT, MICHIGAN

CURTAIN-ROD CORNICE

Application filed January 18, 1930. Serial No. 421,636.

My invention relates to a new and useful improvement in a curtain rod cornice and has for its object the provision of a device whereby a curtain rod, shade roller, drape support, etc., may be hung on a window frame and concealed from view so as to provide an attractive and ornamental fixture.

Another object of the invention is the provision of an adjustable cornice of this class which will be simple in structure, economical of manufacture, and highly efficient in use.

Another object of the invention is the provision of a cornice of this class having its various supporting parts arranged so that they may be easily and quickly detached and adjusted to various sizes.

Another object of the invention is the provision of novel means for locking the parts in various adjusted positions.

Other objects will appear hereinafter.

The invention consists in the combination and arrangement of parts hereinafter described and claimed.

The invention will be best understood by a reference to the accompanying drawings which form a part of this specification and in which,

Fig. 1 is a front elevational view of the window showing the invention applied.

Fig. 2 is a top plan view of the invention showing it applied.

Fig. 3 is a view taken on line 3—3 of Fig. 2.

Fig. 4 is a view taken on line 4—4 of Fig. 2.

Fig. 5 is a view taken on line 5—5 of Fig. 4.

Fig. 6 is a view taken on line 6—6 of Fig. 1.

Fig. 7 is a view taken on line 7—7 of Fig. 2.

Fig. 8 is a perspective view of one of the connections used in the invention.

I have illustrated the invention used with a window having a casing provided with the top rail 11 projecting outwardly from which are supporting hooks 12 and 13 at opposite sides of the window. The cornice proper is

preferably formed from wood although it may also be formed from metal or other suitable material and is preferably formed with a pattern on its outer face and with a finish to correspond to the interior finish of the room in which mounted. This cornice comprises

the front or central portion 14 to which is hingedly connected the side pieces 15 and 16, the angularity of these side pieces of the central portion 14 determining the width of the structure. By swinging the members 15 and 16 inwardly or outwardly of the central portion 14, through the action of the adjusting rods 43 and 42, the device may be accommodated to narrower or wider windows. Mounted on the end of each of the end pieces 15 and 16 are hinges comprising the leaves 17 and 18 having an opening formed therein as clearly appears in Fig. 5.

Extending parallel to the central portion 14 of the cornice is a curtain supporting rod 19 having the ends 20 and 21 swingably connected thereto. A hinge leaf 22 is provided on its upper edge with a channel 23 in which engages the end piece 21. The structure at opposite ends of the device is the same so that a description of the structure at one end will suffice for both. The leaf 22 is provided with the knuckles 24 which interlace with the knuckles 25 formed on the hinge leaf or plate 26, and a suitable pintle 25' is projected through these knuckles to hingedly connect these parts together. The leaf or plate 26 is provided with the open knuckle or hook 27 which extends over the end piece 21 and is adapted to engage in the opening or eyelet formed in the leaf 18 so as to lock the end piece 15 or the end piece 16 in position. The leaf 18 is provided with a fork 18' which is adapted to embrace the pintle 25'. A supporting eyelet 28 extends upwardly from the plate or leaf 26 and engages the hook 12 or 13 to support the device on the rail 11.

Formed in the leaf or plate 26 is an opening 29. A bracket 30 having its upper end 32 and its lower end 31 angularly turned serves as a support for the swingable bracket 33 which is provided with the slot 34 for the reception of the trunnion 35 carried by the roller 36 of the shade 37. Extending parallel to and positioned inwardly of the central body 14 and outwardly of the curtain rod 19 is a rod 38 which may be used for supporting drapes 38', or the like. Each end of this rod 38 is provided with a hinged extension 39 which projects over the end piece 21 and is

provided with a socket for reception of the pin 40 which projects upwardly from the end piece 21. The end of the member 39 is angularly turned as at 41 and extended into the opening 29 so as to engage the leaf spring 41' which extends outwardly from the end of the locking strip or adjusting rod which comprises the pair of telescope parts 42 and 43 held in their various position of telescopic adjustment by the bolt 44 and the wing nut 44'. Each end of this adjusting rod is formed similar and provided with a projection 45 on one of its faces which is adapted to engage in the opening 29, this projection being formed in a plate 46' cut away as at 46. A keeper 47 is pivotally mounted by the rivet 48 to the member 46' at one end of the sections 42 or 43. When the projection 45 is engaged in the opening 29 the keeper 47 may be swung to the position shown in Fig. 5 and the projection thus locked in the opening 29.

In use the sections 42 and 43 are adjusted to the proper length. The plate 26 is then swung to position so as to engage the hook 27 in the opening of the leaf 18 at the same time the fork 18' is brought into embracing relation with the pintle 25'. As the plate 26 is then swung angularly to the plate 22, the leaf 18 is locked in position on the hook 27, and the end 39 which has been previously brought into crossing relation with the member 21 or the member 20 engages in the opening 29. The projection 45 is then projected into the opening 29 and the keeper 47 is moved to locking position thus locking the plate 29 against swingable movement by securing the device in its adjusted position.

I have illustrated the curtain 52 provided with rings 53 which are slidably mounted on the rod 19. Secured to this rod are brackets 54 and 55 which serve to support pulleys 56 and 57 over which are extended the cords 58 and 59. The cord 58 is brought around the pulley 57 and around the pulley 56 and fastened at 60 to the end ring of the curtain 52'. The cord 59 is brought over the pulley 57 and fastened at 61 to the end ring 62 of the curtain 52. This cord then passes around the pulley 56 and depends therefrom so that when the cords at one end of the window are drawn downwardly the curtain may be moved to open position and when drawn downward at the opposite side of the window the curtain is moved to closed position.

With a cornice constructed in this manner the advantages sought for are attained and a durable structure is provided which may be easily and quickly mounted in position and easily and quickly adjusted to various positions.

While I have illustrated and described the preferred form of construction I do not wish to limit myself to the precise details of structure shown but desire to avail myself of such

variations and modifications as may come within the scope of the appended claims.

Having thus described my invention what I claim as new and desire to secure by Letters Patent is:

1. A curtain rod cornice of the class described, comprising: a central cornice forming member; a side piece swingably connected to each end of said central cornice forming member; a hinge mounted on the inner surface of each of said side pieces, one end of said hinge being free for swingable movement relatively to the side piece on which mounted and provided with an opening formed therein; a telescoping adjusting rod extending parallel to said central cornice forming member and positioned rearwardly thereof; a hinge leaf secured to each end of said adjusting rod; and a hook on said hinge leaf engageable with the opening on said free end of said hinge and securing said side pieces in fixed relation to said adjusting rod. 70 75 80 85

2. A device of the class described, comprising: a central cornice member; a side piece swingably mounted on each end of said cornice member; a hinge mounted on the inner surface of each of said side pieces and having one end free for swingable movement relatively thereto, said free end having an opening formed therein; an adjusting rod extending parallel to said central portion and positioned rearwardly thereof in spaced relation thereto; a hinge leaf having an opening formed therein; a projection mounted on each end of said adjusting rod for engaging in the opening in said hinge leaf; means on said adjusting rod for locking said projection in said opening, and a hook on said hinge leaf engageable in the opening formed in said free end of said hinge for locking said side pieces against swingable movement. 90 95 100 105

3. A device of the class described, comprising: a central cornice member; a side piece swingably mounted on each end of said cornice member; a hinge mounted on the inner surface of each of said side pieces and having one end free for swingable movement relatively thereto, said free end having an opening formed therein; an adjusting rod extending parallel to said central portion and positioned rearwardly thereof in spaced relation thereto; a hinge leaf having an opening formed therein; a projection mounted on each end of said adjusting rod for engaging in the opening in said hinge leaf; means on said adjusting rod for locking said projection in said opening, and a hook on said hinge leaf engageable in the opening formed in said free end of said hinge for locking said side pieces against swingable movement. 110 115

4. A device of the class described, comprising: a central cornice member; a side piece swingably mounted on each end of said cornice member; a hinge mounted on the inner surface of each of said side pieces and having one end free for swingable movement relatively thereto, said free end having an opening formed therein; an adjusting rod extending parallel to said central portion and positioned rearwardly thereof in spaced relation thereto; a hinge leaf having an opening formed therein; a projection mounted on each end of said adjusting rod for engaging in the opening in said hinge leaf; means on said adjusting rod for locking said projection in said opening, and a hook on said hinge leaf engageable in the opening formed in said free end of said hinge for locking said side pieces against swingable movement; a second hinge leaf swingably mounted on said first mentioned hinge leaf; a pair of supporting rods positioned between said adjusting rod and said central portion; a swingably mounted end piece on each of supporting rods 120 125 130

the end pieces on one of said supporting rods extending across the end pieces on the other of said supporting rods; a channel bearing member mounted on said second mentioned hinge leaf for the reception of the end pieces of one of said supporting rods.

4. A device of the class described, comprising: a central cornice member; a side piece swingably mounted on each end of said cornice member; a hinge mounted on the inner surface of each of said side pieces and having one end free for swingable movement relatively thereto, said free end having an opening formed therein; an adjusting rod extending parallel to said central portion and positioned rearwardly thereof in spaced relation thereto; a hinge leaf having an opening formed therein; a projection mounted on each end of said adjusting rod for engaging in the opening in said hinge leaf; means on said adjusting rod for locking said projection in said opening, and a hook on said hinge leaf engageable in the opening formed in said free end of said hinge for locking said side pieces against swingable movement; a second hinge leaf swingably mounted on said first mentioned hinge leaf; a pair of supporting rods positioned between said adjusting rod and said central portion; a swingably mounted end piece on each of supporting rods the end pieces on one of said supporting rods extending across the end pieces on the other of said supporting rods; a channel bearing member mounted on said second mentioned hinge leaf for the reception of the end pieces of one of said supporting rods; and means for locking said end piece in said channel bearing member.

5. A device of the class described, comprising: a central cornice member; a side piece swingably mounted on each end of said cornice member; a hinge mounted on the inner surface of each of said side pieces and having one end free for swingable movement relatively thereto, said free end having an opening formed therein; an adjusting rod extending parallel to said central portion and positioned rearwardly thereof in spaced relation thereto; a hinge leaf having an opening formed therein; a projection mounted on each end of said adjusting rod for engaging in the opening in said hinge leaf; means on said adjusting rod for locking said projection in said opening, and a hook on said hinge leaf engageable in the opening formed in said free end of said hinge for locking said side pieces against swingable movement; a second hinge leaf swingably mounted on said first mentioned hinge leaf; a pair of supporting rods positioned between said adjusting rod and said central portion; a swingably mounted end piece on each of the supporting rods the end pieces on one of said supporting rods extending across the end pieces on the other of said supporting rods;

a channel bearing member mounted on said second mentioned hinge leaf for the reception of the end pieces of one of said supporting rods; and a bracket carried by said second mentioned hinge leaf; and a bracket swingably mounted on said bracket.

In testimony whereof I have signed the foregoing specification.

JOHN AJEMIAN.
